(57) **CLAIM**

The ornamental design for a webcam cover, as shown and described.

DESCRIPTION

FIG. 1 is a perspective view of a webcam cover of the present invention shown covering the built-in webcam of a laptop computer.

FIG. 2 is a front elevation view thereof.

FIG. 3 is a rear elevation view thereof.

FIG. 4 is a top view thereof.

FIG. 5 is a bottom view thereof.

FIG. 6 is a right side elevation view thereof; and,

FIG. 7 is a left side elevation view thereof.

The broken lines shown in FIG. 1 illustrate features of the article to which the design is applied that form no part of the claimed design.

1 Claim, 3 Drawing Sheets(56)
